UNITED STATES PATENT OFFICE.

MAX GARBELL, OF CHICAGO, ILLINOIS.

DESIGN FOR A FRAME FOR TYPEWRITING MACHINES.

Application filed February 6, 1925. Serial No. 12,283. Term of patent 14 years.

To all whom it may concern:

Be it known that I, MAX GARBELL, a citizen of the United States, residing at Chicago, in the county of Cook and State of Illinois, have invented a new, original, and ornamental Design for Frames for Typewriting Machines, of which the following is a specification, reference being had to the accompanying drawing, forming a part thereof.

The figure is a perspective view of a frame for typewriting machines, showing my new design. The characteristic feature of the

design comprises a top plate, the rear vertical wall of which embodies in a continuous sweeping curve the sections adjacent the ribbon spool containers and the intermediate bowed section, said intermediate section merging at its center with the front vertical wall of the top plate.

I claim:

The ornamental design for a frame for typewriting machines, as shown and described.

MAX GARBELL.
